SAFETY DEVICE

Harry A. Fine, Flushing, N. Y., assignor to I. B.
Kleinert Rubber Company, New York, N. Y.

Application August 14, 1935, Serial No. 36,160

18 Claims. (Cl. 192—130)

The present invention relates to safety devices for apparatus comprising reciprocating tools, and more particularly to safety devices for die presses and similar apparatus.

5 One object of the invention is to provide such apparatus with means to protect the operator against injury.

Another object of the invention is to provide a press or other apparatus having a reciprocating plunger or tool with means to positively engage a movable part of the apparatus to prevent movement thereof except upon actuation of said means to release said movable part.

Another object of the invention is to provide 15 such apparatus with a safety latch to hold the plunger or tool in retracted position so that said tool or plunger cannot be operated without first releasing said latch.

A further object of the invention is to provide 20 such apparatus with means to move the operator's hand or fingers out of the path of the plunger during the movement of the latter to projected position.

The above objects of the invention and other 25 objects ancillary thereto will best be understood from the following description considered in connection with the accompanying drawings.

In the drawings:

Fig. 1 is a side view of a press provided with the 30 safety devices of the present invention;

Fig. 2 is a front view of the press shown in Fig. 1;

Fig. 3 is a sectional view on the line 3—3 of Fig. 1;

Fig. 4 is a sectional view on the line 4—4 of Fig. 5;

Fig. 5 is a front view of the latch mechanism and the mounting plate therefor;

Fig. 6 is a sectional view on the line 6—6 of Fig. 3;

Fig. 7 is a sectional view on line 7—7 of Fig. 5; and

Fig. 8 is a sectional view on the line 8—8 of Fig. 2.

45 The safety devices of the present invention are intended primarily for use in connection with foot-operated presses of the type in which a reciprocating plunger carrying a tool or a die is moved with relation to a complementary member 50 such as an anvil or die positioned therebelow, and, more particularly, for use in connection with such presses which are utilized for securing parts of separable fastener elements, such as the button and socket parts of snap fasteners, to articles 55 provided with such fasteners. It will be under-

stood, however, that the present safety devices may be employed in association with presses utilized for other purposes as well as with apparatus having other tools, such as cutting and punching tools.

5 In the specific embodiment illustrated herein, one of the safety devices comprises a member pivoted to a stationary part of the press and normally positioned so as to prevent movement of the plunger into engagement with the complementary die or anvil, but movable to release the plunger to permit the latter to be projected for accomplishing its function. The other safety device, as illustrated herein, comprises a guard member which is operated under the control of 10 the mechanism for actuating the plunger to move the operator's hands or fingers out of the path of the plunger should the operator inadvertently fail to remove his hands or fingers out of said path when operating the press while the latch is released or when the press is not equipped with 15 said latch or other positive stop member.

The apparatus here shown as equipped with the safety devices of the present invention comprises a foot-operated press including a yoke frame 10 mounted on a base or stand 12. The upper part of the yoke frame is provided with horizontally extending and vertically spaced bearing members 14 and 16 within which the machine tool here shown as a cylindrical plunger 18 is slidably mounted. At the lower part of the frame below the plunger 18 and in the path of the latter, there is a stationary member 20 which is screw-threaded, as shown, for vertical adjustment on the frame, a set screw 22 being provided 20 for releasably holding said member 20 against rotation in adjusted position. The plunger 18 25 may carry a die 24 and the stationary member 20 may be provided with a complementary die or work support 26. The plunger 18 is held in 30 normally retracted position by means of a helical spring 28 which is disposed about said plunger and bears at one end on the bearing 16 and at its other end against the pin 30 which, in the normally retracted position of the plunger 18, abuts 35 the lower surface of the bearing member 14 to limit the upward movement of the plunger. An upper surface portion 32 of the plunger is flattened and is in slidable engagement with the flat end of a screw 34 to prevent the plunger from 40 rotating in its bearings 14 and 16.

The tool 18 is moved to projected or work-engaging position by means of a pivoted lever 36 mounted on a pin 38 in the horizontally-spaced vertically-extending bearing members 39. The 45 50 55

rear end of the lever 36 has a pivotal connection 40 with one arm 42 of a toggle lever, the other arm 44 of the toggle lever having a fixed pivotal connection 46 with the yoke frame 10. Said arms 42 and 44 are pivotally connected by a transversely extending pin 48 disposed for sliding movement in the slots 50 of the bifurcated portion 52 of the operating lever 54. Said operating lever is pivotally mounted on a pivot pin 56 carried by a bracket 58 which depends from the base 12. The lower end of the operating lever 54 is provided with a treadle 60. Thus, by exerting pressure on the treadle 60, the operating lever 54 is caused to operate the toggle lever thereby to 15 actuate the lever 36, whereby the forward portion of the latter is brought into engagement with the upper end of the plunger 18 for moving said plunger to projected or work-engaging position against the pressure of the spring 28.

20 In order to prevent inadvertent projection of the plunger or the tool carried thereby to work-engaging position, there is provided a safety device comprising a stop member 62 which is normally disposed in the path of movement of the pin 30 whereby to engage the latter and positively prevent the movement of the plunger. Said stop member 62 is pivotally mounted at its lower end on a pivot pin 64 fixed to and projected from the inner face of the mounting plate 66 which is secured by screws 67 to the upper forward part of the yoke frame 10 adjacent the bearings 14 and 16. An operating lever 68 having a finger piece 69 is pivotally mounted on a screw bearing 70 positioned above the pivot pin 64 and is connected to the stop member 62 by a screw stud 72. Said stud 72 is secured in fixed relation to the upper end of the stop member 62 and extends through a slot 74 provided at the upper end of said operating lever. Said screw stud 72 extends from the stop member 62 at one side of the plate 66 over the inwardly off-set edge 76 of the latter to the other side thereof and into the slot 74 of the operating lever 68. The width of the slot 74 is approximately equal to the diameter of the screw stud 72, whereby rotation of the movement of the lever 68 from the position shown in full lines to the position shown in dotted lines in Fig. 1, is effective to move the stop arm out of the path of the pin member 30 to permit the tool to be projected to work-engaging position. It will be observed that while the stop member 62 and the operating lever 68 are mounted on different centres of rotation, the provision of the slot 74 permits said movement of the stop member 62 and by reason of the limited length of said slot, the movement of the stop member 62 to tool releasing position is limited by the engagement of the shank of the screw stud 72 with one end of said slot. When the operating lever 68 is released, it is returned to normal locking position in the path of the member 30, against the shoulder 77 on the plate 66, by means of a tension spring 78 having one end secured to the upper end 69 of the operating lever 68, and its other end secured to the bearing 39. Thus, it is seen that the tool cannot be moved to work-engaging position, unless the safety device is operated to move the stop member 62 out of the path of the pin 30, and the operator of the apparatus is therefore protected against injury due to the inadvertent actuation of the plunger or the tool carried thereby.

For the purpose of affording added protection to the operator of apparatus of the type herein contemplated, an additional safety device is pro-

vided in accordance with the present invention, and it is intended that said device, although useful by itself, shall be utilized together with the plunger stop device described above. The additional safety device comprises a guard member 80 which is mounted for movement adjacent the stationary member 20, or the die 26 carried thereby, substantially in the plane of the work support surface and transversely of the path of the tool 18.

The guard 80 comprises a plate having an elongated slot 82, which is about as wide as the diameter of the stationary die member 26, and is defined by the spaced longitudinally extending arms 84. The guard member 80 has a saddle portion 86 provided with downwardly reflexed side portions 88 and 90 in slidable engagement with a block 92. The saddle 86 is adjustably secured to the block 92 by means of a set screw 94 which projects through an elongated opening 96 in said side portion 88 and is threaded into an opening 98 in the block 92. The guard member 80 may be adjusted vertically with respect to the die member 26 by sliding the saddle 86 in engagement with the sides of the block 92. Said reflexed side portion 88 is positioned within a groove 89 in the side of the block 92 whereby movement of the saddle longitudinally of the block is prevented.

The block 92 is provided with a bore 93 which receives one end of an operating rod 100. The block 92 is adjustably secured to the rod 100 by a screw 102, which projects through a slot 97 provided in the side portion 90 of the saddle 86. It will be observed that the shank of the saddle adjusting screw 94 terminates short of the rod 93 so as not to interfere with the longitudinal movement of the block 92 on the operating rod 100, and it will be observed also that the slot 97 permits vertical adjustment of the saddle 86 with respect to the block 92. The operating rod 100 is slidably mounted in a bore 104 in the yoke frame 10 and terminates in a free end 106 disposed adjacent to the main operating lever 54 below the arm 44 of the toggle lever. The operating rod 100 is normally retained in retracted position by a spring 108 disposed about said rod and having one end bearing against the yoke frame 10 and its other end bearing against a collar 110, secured at the end of the operating rod 100.

In the normal position of the parts, prior to the projection of the tool to work-engaging position, the guard 80 is in retracted position with the end 106 of the rod 100 closely adjacent to or in contact with the operating lever 54. Upon movement of said rod 54 to project the tool to work-engaging position, the operating rod 100 is moved against the pressure of the spring 108 transversely of the path of movement of the plunger 18 and the tool carried thereby. Thus, should the operator of the apparatus inadvertently fail to remove his hands or fingers from the path of the tool, the movement of the guard 80 will either move the operator's hands or fingers out of the path of said tool or will call the operator's attention to his danger, thus greatly minimizing, if not entirely eliminating, the chances of injury.

It is apparent from the above description of the safety devices of the present invention, that both of said devices contribute to protect the operator against injury by the plunger or the tool carried thereby. In most, if not all cases, the releasable stop member will be effective to prevent injury to the operator, since the plunger cannot be reciprocated unless the stop member is

released. However, should the operator release the stop member and for some reason fail to remove his hand or fingers from the path of the plunger, the reciprocating guard, by moving 5 transversely of said path, will either push the operator's hands or fingers out of said path or, by engagement with the operator's hands or fingers if the latter are in the path of the plunger, will awaken the operator to his danger so that 10 the latter will have an opportunity to remove his fingers before the plunger or tool is fully projected.

Thus, it is seen that the safety devices of the present invention are well adapted to accomplish the several objects of the invention. It will be 15 understood, however, that certain changes in the construction and arrangement of parts may be made and that certain of the parts may be used without others. Accordingly, I do not wish to be limited to the precise constructions herein shown, 20 except as may be required by the appended claims and the prior art.

Having thus described my invention, what I claim and desire to secure by Letters Patent of the United States is:

25 1. Apparatus comprising a frame, a tool mounted in said frame for movement to retracted position and to work-engaging position, and releasable means for preventing movement of said tool to work-engaging position, said means comprising a member in fixed relation to said tool and movable therewith, a stop member pivotally mounted on said frame in the path of movement of said first member to engage the latter and thereby prevent movement of said tool to work- 30 engaging position and movable out of said path to permit movement of said tool to work-engaging position, and a lever pivotally mounted on said frame and having an operative connection with said stop member for moving the latter out of 35 said path, said lever having a slot and said connection comprising a stud fixed to said stop member and projecting into said slot for engagement with said lever, said stud having limited movement in said slot to limit the movement of said 40 45 stop member.

2. Apparatus comprising a frame, a tool mounted in said frame for movement to retracted position and to work-engaging position, and releasable means for preventing movement of said tool to work-engaging position, said means comprising a member in fixed relation to said tool and movable therewith, a stop member pivotally mounted on said frame in the path of movement of said first member to engage the latter and thereby prevent movement of said tool to work-engaging position and movable out of said path to permit movement of said tool to work-engaging position, a lever pivotally mounted on said frame above the pivot of said stop member, said lever 50 having a slot above its pivot, and a stud connected to said stop member and having movement in said slot whereby pivotal movement of said lever in one direction is effective to move said stop member out of said path.

60 65 70 75 3. Apparatus comprising a frame, a tool mounted in said frame for movement to retracted position and to work-engaging position, and releasable means for preventing movement of said tool to work-engaging position, said means comprising a member in fixed relation to said tool and movable therewith, a stop member pivotally mounted on said frame in the path of movement of said first member to engage the latter and thereby prevent movement of said tool to work- 75 engaging position and movable out of said path

to permit movement of said tool to work-engaging position, a lever pivotally mounted on said frame above the pivot of said stop member, said lever having a slot above its pivot, and a stud connected to said stop member and having movement in said slot whereby pivotal movement of said lever in one direction is effective to move said stop member out of said path, said stud having a limited movement in relation to said slot to limit the movement of said stop member. 10

4. Apparatus comprising a frame, a tool mounted in said frame for reciprocating movement to retracted position and to work-engaging position, releasable stop means in the path of said tool to prevent movement thereof to work-engaging position, a guard movable transversely of the path of said tool, and means for simultaneously moving said tool and said guard when said stop means is released. 15

5. Apparatus comprising a frame, a tool mounted in said frame for reciprocating movement to retracted position and to work-engaging position, releasable stop means in the path of said tool to prevent movement thereof to work-engaging position, a guard comprising spaced arms movable 20 transversely of the path of said tool, and means for simultaneously moving said tool and said guard when said stop means is released. 25

6. Apparatus comprising a frame, a tool slidably mounted in said frame for reciprocating movement to retracted position and to work-engaging position, a work-supporting member mounted on said frame below and in the path of said tool, releasable stop means to prevent movement of said tool to work-engaging position, 30 a slotted guard-plate movable transversely of said work-supporting member substantially adjacent the work-supporting surface of the latter, and means for simultaneously moving said tool and said guard-plate when said stop means is released. 35

7. Apparatus comprising a stationary frame, a tool mounted in said frame for movement to retracted position and to work-engaging position, a stationary member on said frame in the path 45 of said tool adapted to receive the work to be acted upon by the tool, a guard member mounted on said stationary frame for movement adjacent said stationary member transversely of the path of said tool, means for actuating said tool, and 50 means for automatically moving said guard when said tool is actuated.

8. Apparatus comprising a stationary frame, a tool mounted in said frame for movement to retracted position and to work-engaging position, a stationary member on said frame in the path of said tool adapted to receive the work to be acted upon by the tool, a guard member mounted on said stationary frame for movement adjacent said stationary member transversely of the path of said tool, means for actuating said tool, said guard comprising spaced arms disposed at opposite sides of said stationary member, and means for automatically moving said guard when said tool is actuated. 65

9. Apparatus comprising a stationary frame, a tool mounted in said frame for movement to retracted position and to work-engaging position, a stationary member on said frame in the path of said tool adapted to receive the work 70 to be acted upon by the tool, a guard member mounted on said stationary frame for movement adjacent said stationary member transversely of the path of said tool, a rod for actuating said guard, and a lever having an operative con- 75

nection with said tool and with said rod for moving said guard when the tool is moved to work-engaging position.

10. Apparatus comprising a frame, a tool mounted in said frame for movement to retracted position and to work-engaging position, a stationary member on said frame in the path of said tool adapted to receive the work to be acted upon by the tool, a guard member mounted on said frame for movement adjacent said stationary member transversely of the path of said tool, said frame having a bore, a rod connected to said guard and slidably in said bore, a lever bearing on the end of said rod and having an operative connection with said tool whereby the guard is actuated simultaneously with the actuation of said tool to work-engaging position.

11. Apparatus comprising a frame, a tool mounted in said frame for movement to retracted position and to work-engaging position, a stationary member on said frame in the path of said tool adapted to receive the work to be acted upon by the tool, a rod slidably mounted in said frame for movement transversely of the path of said tool, a block secured to said rod, a guard member adjustably secured to said block and positioned adjacent said stationary member for movement transversely of the path of said tool, means for actuating said tool, and means for automatically moving said guard when the tool is actuated.

12. Apparatus comprising a frame, a tool mounted in said frame for movement to retracted position and to work-engaging position, a support for the work engaged by said tool, releasable means for preventing movement of said tool to work-engaging position, said means comprising a member in fixed relation to said tool and movable therewith, a stop member pivotally mounted at one end thereof on said frame and having its opposite end in position normally to engage said movable member to prevent movement of said tool to work-engaging position, a lever mounted on said frame on a pivot in offset relation to the pivot of said stop member, and a connection between said lever and said stop member whereby pivotal movement of said lever in one direction is effective to move said stop member out of said normal position to permit movement of said tool, said connection being effective in itself to limit said movement of the lever and stop member.

13. Apparatus comprising a frame, a tool mounted in said frame for movement to retracted position and to work-engaging position, a support for the work engaged by said tool, releasable means for preventing movement of said tool to work-engaging position, said means comprising a member in fixed relation to said tool and movable therewith, a stop member pivotally mounted at one end thereof on said frame and having its opposite end in position normally to engage said movable member to prevent movement of said tool to work-engaging position, a lever mounted on said frame on a pivot in offset relation to the pivot of said stop member, and a pin and slot connection between said lever and said stop member whereby pivotal movement of said lever in one direction is effective to move said stop member out of said normal position to permit movement of said tool, said connection being effective in itself to limit said movement of the lever and stop member.

14. Apparatus comprising a stationary frame,

a tool mounted in said frame for movement to retracted position and to work-engaging position, a stationary member on said frame in the path of said tool adapted to receive the work to be acted upon by the tool, a guard member mounted on said stationary frame for movement adjacent said stationary member transversely of the path of said tool, means for adjusting the position of said guard member in relation to said work-receiving member, means for actuating said tool, and means for automatically moving said guard when said tool is actuated.

15. Apparatus comprising a stationary frame, a tool mounted in said frame for movement to retracted position and to work-engaging position, a stationary member on said frame in the path of said tool adapted to receive the work to be acted upon by the tool, a guard member mounted on said stationary frame for movement adjacent said stationary member transversely of the path of said tool, means for adjusting the position of said guard member in relation to said work-receiving member, means for actuating said tool, said guard comprising spaced arms disposed at opposite sides of said stationary member, and means for automatically moving said guard when said tool is actuated.

16. Apparatus comprising a stationary frame, a tool mounted in said frame for movement to retracted position and to work-engaging position, a stationary member on said frame in the path of said tool adapted to receive the work to be acted upon by the tool, a guard member mounted on said stationary frame for movement adjacent said stationary member transversely of the path of said tool, a rod for actuating said guard, a connection between said rod and guard providing means for adjusting the position of said guard laterally of said rod, and a lever having an operative connection with said tool and with said rod for moving said guard when the tool is moved to work-engaging position.

17. Apparatus comprising a stationary frame, a tool mounted in said frame for movement to retracted position and to work-engaging position, a stationary member on said frame in the path of said tool adapted to receive the work to be acted upon by the tool, said member being adjustable toward and away from said tool, a guard member mounted on said stationary frame for movement adjacent said adjustable member transversely of the path of said tool, means for adjusting said guard toward and away from said tool, means for actuating said tool, and means for automatically moving said guard when said tool is actuated.

18. Apparatus comprising a frame, a tool mounted in said frame for movement to retracted position and to work-engaging position, a stationary member on said frame in the path of said tool adapted to receive the work to be acted upon by the tool, said member being adjustable toward and away from said tool, a rod slidably mounted in said frame for movement transversely of the path of said tool, a block secured to said rod, a guard member adjustably secured to said block and positioned adjacent said stationary member for movement transversely of the path of said tool, means for actuating said tool, and means for automatically moving said guard when the tool is actuated.
